FIG.1

FIG.4

FIG.3

FIG.2

FIG.5

FIG.6

FIG. 7

FIG. 8

FIG. 1 is a front and side perspective view of an instrument for use in measuring sizes, dimensions and the like, showing my new design.

FIG. 2 is a front perspective view thereof.

FIG. 3 is a top plan view thereof.

FIG. 4 is a front and side perspective view of another embodiment of the design.

FIG. 5 is a front perspective view of the design embodiment shown in FIG. 4.

FIG. 6 is a top plan view of the embodiment shown in FIG. 4.

FIG. 7 is a rear perspective view of FIG. 2.

FIG. 8 is a rear perspective view of FIG. 5.

The undisclosed side of the measuring instrument is the same in appearance as the side shown.

The dominant features of the design reside in the portions shown in full lines.

This is a continuation-in-part of application Serial No. D. 78,737, filed February 24, 1964.

I claim:

The ornamental design for an instrument for use in measuring sizes, dimensions, and the like, substantially as shown and described.
